UNITED STATES PATENT OFFICE.

HARRY E. DOERR, OF ST. LOUIS, MISSOURI, ASSIGNOR TO SCULLIN-GALLAGHER IRON & STEEL COMPANY, OF ST. LOUIS, MISSOURI, A CORPORATION OF MISSOURI

RAILWAY-CAR TRUCK.

1,101,621.

Specification of Letters Patent. Patented June 30, 1914.

Application filed October 27, 1913. Serial No. 797,565.

To all whom it may concern:

Be it known that I, HARRY E. DOERR, a citizen of the United States, residing at St. Louis, Missouri, have invented a certain new and useful Improvement in Railway-Car Trucks, of which the following is a full, clear, and exact description, such as will enable others skilled in the art to which it appertains to make and use the same.

10 This invention relates to railway car trucks, and particularly to freight car truck side frames.

The main object of my present invention is to provide a cast metal side frame for 15 freight car trucks, which is so designed that standard Master Car Builders passenger car journal boxes can be used with same.

Other objects and desirable features of my invention will be hereinafter pointed out.

20 Figure 1 of the drawings is a side elevational view of a portion of a freight car truck side frame constructed in accordance with my invention, one of the journal boxes being shown in vertical section; Fig. 2 is an 25 end elevational view of the side frame, showing the journal box in elevation; Fig. 3 is a horizontal sectional view taken on the line 3—3 of Fig. 1; Fig. 4 is a vertical sectional view taken on the line 4—4 of Fig. 1; Fig. 30 5 is a side elevational view illustrating a slight modification of my invention; Fig. 6 is a vertical transverse sectional view taken on the line 6—6 of Fig. 5, showing the journal box in elevation; Figs. 7, 9 and 11 are 35 side elevational views illustrating other modifications of my invention; Fig. 8 is a vertical transverse sectional view taken on the line 8—8 of Fig. 7, showing the journal box in elevation; Fig. 10 is a vertical trans- 40 verse sectional view taken on the line 10—10 of Fig. 9, showing the journal box in elevation; and Fig. 12 is an end view of the said view shown in Fig. 11 with the journal box removed.

45 Referring to Fig. 1 of the drawings, which illustrates the preferred form of my invention, A designates a cast metal freight car truck side frame, which is provided with integral pedestal jaws 1 for receiving the 50 journal boxes B. The journal boxes B are standard Master Car Builders passenger car boxes, and are provided on their sides with pairs of laterally projecting lugs 2, that extend the entire height of the box, as shown 55 in Fig. 2, which box is also provided on its

sides with a pair of intermediate laterally projecting lugs 3, which are arranged between the lugs 2, and extend parallel to same, as shown in full lines in Fig. 2, and in broken lines in Fig. 3.

The pedestal jaws 1 on the side frame are so designed that they fit snugly between the lugs 2 on the sides of the journal boxes, and also embrace the intermediate lugs 3, and thus prevent the journal boxes from moving 60 transversely of the side frame. In the preferred form of my invention as herein shown, the pedestal jaws do not extend downwardly the full height of the journal box, but terminate a short distance below 65 the center of the journal, so as to facilitate the insertion and removal of said box, and each of the pedestal jaws 1 is provided with a channel-shaped portion 4, that receives the intermediate lugs 3 on one side of the box, 70 the side legs of said channel-shaped portion being provided with laterally projecting flanges 5, as shown in Figs. 2 and 3, that bear against the inner edges of the lugs 2. In other words, each of the pedestal jaws 1 75 is provided with a recess for receiving the intermediate lugs 3 on one side of the box, and is also provided with portions that lie between said intermediate lugs and the lugs 2, thereby securely holding the journal box 80 in position, and preventing it from moving transversely of the side frame. The side frame is, of course, provided with horizontally disposed portions or bearing members 6 that bear upon the upper sides of the journal boxes, and these bearing members 6 are 85 so designed that they fit between the usual parallel lugs 7 on the top side of a standard passenger car journal-box, and are preferably provided on their under sides with 90 transversely disposed recesses 6^a, as shown in Fig. 1, that receive the usual transverse rib 7^a that lies between the parallel lugs 7.

In the form of my invention shown in Figs. 1 to 4, inclusive, no means is provided for positively locking the journal-boxes to the side frame, so as to prevent the boxes from dropping out of the side frame in case the truck becomes derailed, but in Figs. 5 and 6 I have illustrated a structure wherein the journal-boxes are securely locked to the side frame by means of ears 8, on the upper sides of the journal-boxes that project upwardly into pockets 9 formed in the side frame, and which are provided with trans- 105 110

versely disposed openings that receive bolts or retaining devices 10 that pass transversely through the pockets 9, as shown clearly in Fig. 6; the pocket 9 being formed integral with the portions of the center web of the side frame that lie above the horizontally disposed bearing members 6. In other respects the side frame shown in Figs. 5 and 6 is the same as the side frame illustrated in Figs. 1 to 4, inclusive.

Instead of providing each journal-box with an upwardly projecting wing or lug that enters a pocket in the side frame, the box could be provided with a pair of upwardly projecting wings 8^a that embrace a portion 9^a on the side frame of the same width as the horizontally disposed bearing member 6, the wings 8^a being secured to the portion 9^a by means of a bolt or other suitable retaining device 10 that passes transversely through said parts, as shown in Figs. 7 and 8.

In the form illustrated in Figs. 9 and 10, a portion of the side frame above the horizontally disposed bearing member 6 is provided with a laterally projecting lug 9^b that lies between a pair of upwardly projecting lugs 8^b on the top of the journal-box, said lugs being provided with alining perforations for receiving a retaining bolt 10.

In the forms of my invention illustrated in Figs. 5 to 10, inclusive, journal-boxes of special construction are shown, but it will be obvious that in case these special boxes become damaged they may be replaced with standard Master Car Builders boxes.

In the form of my invention illustrated in Figs. 11 and 12, standard Master Car Builders passenger car journal-boxes can be used with the frame without liability of dropping out of the frame in case the truck becomes derailed, as shown in Figs. 11 and 12. The side frame is provided with retaining straps 11 which extend across the

under side of the journal-boxes, and which 45 are secured to the pedestal jaws 1 by means of bolts or other suitable fastening devices 12, as shown clearly in Figs. 11 and 12.

Having thus described my invention, what I claim as new and desire to secure by Letters Patent is:

1. In a car truck, a journal-box, a cast metal side frame provided with an inverted U-shaped portion that embraces said journal-box, each of the depending legs of said portion being provided with a pair of transverse flanges and a channel intermediate said flanges, vertically disposed lugs on the side walls of said journal-box that coöperate with said flanges, and similar lugs on said box intermediate said first-mentioned lugs that coöperate with said channel.

2. In a car truck, a journal-box provided on each of its side walls with two pairs of parallel lugs and on its top wall with a pair 65 of parallel lugs and a transverse-rib extending between said lugs, and a cast metal side frame provided with integral projections that coöperate with the lugs on the side walls of said box and a portion that bears 70 against the top wall of said box and coöperates with said top lugs and transverse rib.

3. In a car truck, a journal-box provided on each of its side walls with two pairs of 75 parallel lugs and on its top wall with a pair of parallel lugs and a transverse rib extending between said lugs, a cast metal side frame provided with portions that coöperate with said lugs and rib, and means for securing said box to said frame.

In testimony whereof I hereunto affix my signature in the presence of two witnesses, this 21st day of October 1913.

HARRY E. DERR.
